SAFETY LIMIT TRIP FOR SPINDLE FEED

David C. Klausmeyer, deceased, late of Cincinnati, Ohio, by H. Henry Sundermann, executor, Cincinnati, Ohio, and Rowland L. Rickwood, Cincinnati, Ohio, assignors to The Cincinnati Bickford Tool Company, Cincinnati, Ohio, a corporation of Ohio

Application July 7, 1931, Serial No. 549,254

12 Claims. (Cl. 77—33)

This invention has to do with drilling machines and relates more particularly to an improved device for interrupting the power feed to the spindle when the latter has reached a predetermined position in its travel, and to a means for supporting the spindle and simultaneously therewith interrupting the power drive, at any point intermediate its extremes of movement should there occur a failure in the counterweighting mechanism.

Heretofore, it has been customary to provide limit feed dogs for throwing out the power drive at the extremes of spindle movement and to locate the fixed trip dogs on the translatable member or in the feed controlling mechanism. Obviously, these devices were inoperative to disconnect the feed until the spindle has travelled its full distance. Furthermore, the adjustable dog customarily employed in depth indicating devices for disconnecting or suspending the feed at the proper depth, merely disconnects the feed and the spindle stands unlocked, supported only by the counterweighting mechanism. Should the counterweighting means fail, the spindle will, of its own weight, drop the full distance with consequent jarring or damaging of the parts or work-pieces and possible injury to the operator.

This invention undertakes to overcome the undesirable features of the prior machines and to provide a simple, compact mechanism for disconnecting the feed immediately upon a failure of the counterweighting mechanism, and in addition thereto to provide means for automatically retaining and supporting the spindle at any point in its travel in the event of such a failure.

Another object of this invention is to construct a device, of but few working parts, that will disconnect the power feed and support the spindle, in emergencies such as above explained, and to render both the manual and power translating means ineffective so long as the parts remain out of their normal position, thereby informing the operator that some portion of the spindle counterweighting mechanism has failed and preventing him from using the machine while it is in an unsafe condition.

Still another object of this invention is to provide a mechanism for restraining untoward downward movement of the spindle instantly upon the failure of the counterpoising mechanism and which will function to support the spindle if the failure occurs when the machine is standing idle or when during the translating

of the spindle by either manual or power means, and, if the inoperativeness occurs during power feeding movements, then to simultaneously disengage the power feed so that no damage will be done to the feed train by reason of a continued application of power.

To attain the objects of this invention it is proposed to provide a machine tool with means for disengaging the power drive at predetermined points in the travel of the driven element and to so arrange the device that the drive will be suspended at any intermediate point in cases of emergency and simultaneously lock the movable element against further movement, accidental or otherwise. The safety device is so arranged as to be ineffective so long as there is the counterpull of the balancing mechanism upon the translatable member. As soon as the balancing means becomes inoperative as a balancing medium, the safety mechanism is thrown into action and immediately suspends and prevents further movement of the movable element.

Other objects and advantages will be in part indicated in the following description and in part rendered apparent therefrom in connection with the annexed drawings.

To enable others skilled in the art so fully to apprehend the underlying features hereof that they may embody the same in the various ways contemplated by this invention, drawings depicting a preferred typical construction have been annexed as a part of this disclosure and, in such drawings, like characters of reference denote corresponding parts throughout all the views, of which:

Figure 1 is a front elevation of a representative type of machine tool incorporating the invention. Fig. 2 is a sectional view of the power feed clutch and tripping mechanism. Fig. 3 is a sectional view substantially along the line 3—3 of Fig. 2. Fig. 4 is a fragmentary view of the trip bar and its associated mechanism. Fig. 5 is a horizontal sectional view of the lower end of the feed trip rod. Fig. 6 is a sectional view of the upper end of the trip bar and latch mechanism. Fig. 7 is a detail of the safety latch member.

Although this invention is illustrated and described in connection with a conventional drilling machine, it will be understood, however, that its use in other types of machine tools is contemplated.

Figure 1 illustrates a drilling machine having a translatable head member 10 in which there

is mounted for translation and rotation the usual spindle 11. In most machines of this type, power for driving the tool or tools is derived from a prime mover 12, which through the arm shaft 13, and through the speed and feed works 5 located within the head passes to the drill spindle 11. Conventional reversing mechanisms such as the reversing clutches 14 (illustrated in dotted lines) are provided for reversing the direction of the drive to the spindle. The ultimate power 10 drive to the spindle feeding means is shown in Figs. 2 and 3 in which a feed shaft 15 conveys power from the feed gears located in the head (in the interests of clarity, these have not been 15 illustrated) to a worm 16 and worm wheel 17 which form part of the feed control head 18.

The worm wheel 17 is secured to, or formed 20 integral with, a sleeve member 19 which is freely rotatable upon a tubular pinion shaft 20 journaled in the head 18. Near one end of the shaft 20 gear teeth are cut forming pinion 21 which meshes with rack teeth 22 carried by the translatable spindle sleeve 23. When the gear 17 and sleeve 19 are clutched to the shaft 20, as 25 will later be described, and rotated, the spindle sleeve 23 and spindle 11 are caused to be translated. It will be understood that the spindle sleeve 23 does not rotate but is translated only and provides suitable bearings for the rotatable 30 spindle 11 mounted therein.

The outer end of the pinion shaft carries a 35 clutch collar 24 to which are secured and rotatable therewith serrated clutch arms 25 that are pivoted at 26. A portion of the clutch arm 25 is provided with serrations or teeth 27 which are adapted to engage similar serrations 29^a formed upon a ring 29 that rotates with the feed 40 worm gear 17. Movement of the clutch arm 25, to bring the serrated portions into engagement with the worm wheel ring serrations, is effected by pins 28 which are fitted within radial bores formed in the clutch collar 24. An axially movable spreader cam 29 provides cam surfaces 30 for moving the pins 28 outwardly and also provides teeth 31 for inter-engagement with teeth 32 formed on the hand levers 33. The control 45 levers 33 are likewise pivoted to the quick return head 24, as at 34, and when either is moved away from the head 18, the pin 29 is shifted inwardly thereby to move pins 28 and levers 25 outwardly against the action of springs 35. Movement of the levers 25 in this direction, engages the teeth 27 with the teeth 28 of the feed worm 50 wheels 17 and effects translation of the spindle by power. Adjusting screws 36 attached to the clutch levers 25 and contacting with the expanding pins 28, are provided for taking up the wear and to adjust the parts so that proper engagement of the elements 27-28 may be effected.

When the control levers 33 are moved toward 55 the head 18, withdrawing clutch pins 28, the springs 35 rock the clutch levers 25 and effect a disengagement of the elements 27-28 and thereby disengaging the power drive. If the hand control levers 33 are then rotated in a transverse plane, the spindle may be translated 60 in either direction by means of the rack and pinion connection previously described.

Normally the weight of the spindle is counterbalanced by suitable mechanism and hence but 65 a slight application of power is required to translate the same, consequently the operator need not and may not have a firm grip upon the levers 33 when translating the spindle by hand. Now, 70 should the spindle counterpoising mechanism

fail under such circumstances, an exceedingly heavy load is suddenly placed upon the pinion gear 21 and thence transmitted to the levers. The additional weight thus imposed unexpectedly, may jar the control levers free from the operator's grasp and the spindle falls rapidly. Unless means are provided for preventing the descent of the spindle under such conditions, there is always the danger of the whirling levers 80 striking the operator, and there inevitably will occur damage to the tool or work-piece or the stripping of the teeth of the pinion 21 when the uncut portion of the spindle rack 22 is reached.

This invention proposes to guard against such an eventuality by arranging a latch mechanism for preventing untoward downward movement of the spindle when the spindle weight equalizing mechanism fails. For this purpose a spindle chain carrier 37 (see Figs. 2 and 4) is secured to 85 the translatable part, preferably to the spindle sleeve, and to which the counterweighting mechanism is attached.

For the purpose of this disclosure, one form of counterbalancing mechanism, indicated generally as *x*, has been illustrated and which, it is believed, will clearly illustrate the principles of this invention, but it will be understood, however, that any of the common devices adapted to relieve in whole or part the weight of the shiftable element, will serve equally well or may be readily adjusted or adapted for use with this invention. All that is necessary is a device that tends normally to maintain the shiftable element substantially in a position of rest or equilibrium 100 so that the element, whether in a drilling machine or any other type of machine tool, if arranged for an up and down movement, will not fall or move of its own weight.

One side of the carrier 37 is provided with a 105 slot 38 adapted to seat an L shaped latch member 39 pivoted thereto at 40. An arm 41 of the latch projects away from the spindle and over the slot provided for the counterbalancing connection 42, which is pivoted to the carrier. The 110 arm 41 is normally held away from that slot by reason of the connection 42. The counterpull of the balancing means normally maintains the link 42 in a position obstructing the path of movement of the latch arm 41.

A second arm 43 of the latch 39 is arranged 115 substantially perpendicular to the arm 41 and projects into a slot or guideway 44, provided by the carrier member 37, and is adapted to be swung into engagement with a slide bar 45 upon the release of the forces tending to maintain the connecting link 42 in the path of movement of the arm 41. Resilient means such as a spring 46, seated within a recess formed in the interference member 39, provides the energy necessary 120 to move the member 39 into engagement with the bar 45 whenever the counter pull on the connection 42 is released and allowing the latch arm 41 to swing.

The bar 45 is substantially stationary in the 125 drill head casing and is provided with a series of abutments 46 of a size adapted to be engaged by the arm 43 of the interference member 39. The bar 45 parallels the spindle 11 and so soon as balancing means *x* fails so that the connecting link 42 permits the interference member to 130 swing, the arm 43 thereof is brought into engagement with the abutments 46 of the bar which securely locks the spindle thereto and thereby arresting the movement thereof.

It will thus be seen that the action of this safety device is automatic and instantaneous upon the failure of the counterbalancing means and is ready at all times to stop the travel of the spindle in cases of emergency whether the spindle is idle, feeding by power, or by manual means. Obviously, similar mechanism may also be employed to prevent a counterweight from falling whenever its connection with the spindle should fail if such type of balancing means is employed.

Stripping of gears will occur, however, if translation of the spindle is stopped during a power feed and, therefore, to prevent damaging of the feed train, it is proposed to disconnect the power drive simultaneously with the failure of counterweighting mechanism and the locking of the spindle.

With that end in view, the hollow feed pinion shaft 20 carries a push bar 47 one end of which engages the end of clutch spreader pin 29 and the other end engages a short lever 48 that is pivotally mounted at 49 upon a portion of the drill head frame. The opposite end of the lever 48 engages the end of a spring pressed push pin 50, also mounted in the frame, and projecting into the path of movement of cam surfaces 51 and 52 carried by the bar 45. Instead of being rigid with the frame, the safety bar 45 is permitted to have a slight float in order that the cam surfaces 51 or 52 may translate the push pin 50. For this purpose, a slot 53 is formed in the trip bar, into which a stud 54 projects for securing the bar to the frame and yet permitting a limited movement thereof. A bearing nut 55 slidably fitted within a recess in the trip bar cooperates with the head of the bolt 54 to hold the parts together.

The cam surfaces 51 and 52 may be formed on the trip bar, or upon a part secured thereto, and projects through, and has a bearing in, a slot 56 formed in a bushing 57 that supports the push pin 50. A coiled spring 58 urges the push pin against the same surfaces 51 and 52 and thus tends to maintain the trip bar in an intermediate position.

Assuming that the power feed is engaged and the heavy spindle is being fed into the work at a predetermined rate and the counterbalancing chain breaks. Immediately, the latch 39 is permitted to swing counter-clockwise and the interference arm 43 is urged against the notches in the trip bar, seats itself therein, and connects the trip rod 45 and spindle together. The spindle continues to feed a slight distance, carrying the trip bar therewith, until cam surface 51 forces the pin 50 outwardly, which movement, through lever 48 and bar 47 moves the spreader cam pin 29 toward the left (Fig. 2) and de-clutches the power drive. As soon as the lost motion in the trip bar 45 has been taken up, further movement is suspended and the spindle locked against falling.

Similarly, when using the hand feed mechanism or when the machine is standing idle, a failure of the counterbalancing means permits the latch member 39 to swing around and engage itself with the trip bar and thereby lock the spindle. Inasmuch as the power feed is not being used under these conditions, the slight axial movement imparted to the trip bar has no effect other than to take up the lost motion and when the end of the slot 53 strikes the stud 54, further movement of the bar 45 and spindle connected therewith, is suspended.

In this way there is provided a simple and highly effective means for preventing injury to operators or damage to expensive machinery, tools or work-pieces occasioned by falling machine elements and a device that is rendered effective, in cases of such emergencies, under any condition of rest or motion of a machine tool so equipped.

As an additional safeguard, the above explained mechanism performs the function of disconnecting the power traverse and rendering the hand traversing means effective when the shiftable element reaches a predetermined position in its travel, as will now be explained.

Ordinarily, a feed trip dog 65, carried by an adjustable feed dial plate 59, is adapted to engage a pin 60 provided by one of the control levers 33, to swing the latter and to thereby automatically disconnect the power feed when the tool reaches a predetermined depth. The feed dial and trip dog are adapted to be clamped in an adjusted position by suitable means, such as clamp lever 61.

However, in order that no damage will be done to the feed pinion 21 or to other elements of the feed train when the spindle reaches a predetermined position, for example the extreme low limit, which would necessarily follow if the operator inadvertently sets the feed dial and trip dog to a position beyond the permissible limit, a safety trip dog 62 carried by the trip bar 45 is provided. This dog is adapted to be engaged by a dog carried by the translatable member, preferably the chain carrier element 37, and when engaged and moved downwardly, the bar 45 also is moved and cam 51 engages and moves the push pin 50 to a position disconnecting the power feed. A separate dog or dogs, independently adjustable upon the spindle sleeve, may alternatively be employed to effect this shifting if desired.

Likewise when feeding the spindle upwardly, there is danger of stripping the gears when the feed pinion reaches the uncut portion of the spindle sleeve, and, therefore, a second safety trip dog 63 is engaged by the chain carrier 37 and lifts the trip bar 45 up. This movement brings cam face 52 into engagement with the push pin 50 and trips out the power feed in a manner previously explained. Although the safety dogs 62 and 63 are illustrated herein as short screws located at the ends of the trip rod, it is obvious that they may be positioned anywhere thereupon or made adjustable if the peculiarities of the tooling operation warrant.

Without further analysis, the foregoing will so fully reveal the gist of this invention that others can, by applying current knowledge, readily adapt it for various utilizations by retaining one or more of the features that, from the standpoint of the prior art, fairly constitute essential characteristics of either the generic or specific aspects of this invention and, therefore, such adaptations should be, and are intended to be, comprehended within the meaning and range of equivalency of the following claims.

Having thus revealed this invention, it is claimed as new and desired to secure the following combinations and elements or equivalents thereof, by Letters Patent of United States:—

1. A machine tool combining a frame; a tool spindle supported thereby; manual and power means for selectively imparting movements to said spindle; control means therefor; counter-

balancing means for said spindle; and means for rendering one of said driving means ineffective upon a failure of said counterbalancing mechanism, said last mentioned means including a 135 translatable trip bar operatively connected with the control means for said driving means, latch mechanism carried by said spindle and controlled by said counterweighting mechanism adapted automatically to engage and translate said trip 19 bar when said counterweighting mechanism fails; and means for limiting the translatory movement of said trip bar.

2. A drilling machine combining a translatable tool spindle; a member carried thereby; means 135 including a power drive and a controlling clutch for translating said spindle; trip mechanism including a shiftable element and means actuated thereby to throw out said clutch; an abutment, carried by said element adapted to be engaged by 20 the member carried by the spindle thereby to shift said element and throw out said clutch and discontinue the power drive when the spindle has reached a predetermined position in its travel; counterbalancing means for said spindle; 25 a normally inoperative latch mechanism carried by the spindle and associated with said counterbalancing means and adapted upon failure of said counterbalancing means to engage and, by movement with the spindle, shift said shiftable 30 element thereby throwing out the power drive and locking the spindle against further movement.

3. A drilling machine combining a tool head; a tool spindle translatable therein; means including a power drive for translating said spindle; clutch means for controlling said power drive; a clutch throw out mechanism including an element having a limited shifting movement in said tool head; counterbalancing mechanism 40 for said spindle; means rendered effective immediately upon the failure of said counterbalancing mechanism for shifting said element thereby to throw out said clutch and discontinue the power drive; and means carried by said spindle adapted upon failure of said counterbalancing means to engage said element thereby to prevent the spindle from dropping from said tool head.

4. A drilling machine combining a translatable 50 tool spindle; means including a power drive for translating said spindle; clutch means for controlling said power drive; a clutch throw out mechanism including a shiftable element; counterbalancing mechanism for said spindle; means rendered effective immediately upon the failure of said counterbalancing mechanism for shifting said element thereby to throw out said clutch and discontinue the power drive; and means also rendered effective by the failure of 55 said counterbalancing mechanism to lock the spindle against movement in either direction.

5. In a drilling machine, a head; a spindle translatable in said head; power means including a controlling clutch for translating said spindle; 65 means connected with said spindle to counterbalance the weight thereof; a member having a limited sliding movement in said head; a latch device carried by said spindle and normally maintained out of engagement with said slide- 70 able member; means rendered effective by the failure of said counterbalance to cause said latch device to engage said member thereby to lock said member to said spindle whereby the member has a slight movement with the spindle; a 75 cam on said slideable member; and means in-

cluding an element engaging said cam and actuated by the movement thereof for throwing out said clutch and rendering the power means ineffective.

6. In a drilling machine, a head; a spindle translatable in said head; power means including a controlling clutch for translating said spindle; means connected with said spindle to counterbalance the weight thereof; a member having a limited sliding movement in said head; a latch device carried by said spindle and normally maintained out of engagement with said slideable member; means rendered effective by the failure of said counterbalance to cause said latch device to engage said member thereby to lock said member to said spindle whereby the member has a slight movement with the spindle; a cam on said slideable member; means including an element engaging said cam and actuated by the movement thereof for throwing out said clutch and rendering the power means ineffective; and means to prevent re-engagement of said clutch.

7. In a drilling machine, a head; a spindle translatable mounted therein; a counterbalance 100 for said spindle; power means for translating said spindle; a member mounted in said head substantially parallel with the spindle and having a limited sliding movement in said head; means carried by said spindle and adapted immediately upon failure of said counterbalance to engage said member to cause it to be moved a limited distance, with said spindle and then to lock said spindle against dropping; a cam on 105 said member; and means actuated by said cam during the sliding movement of said member to render ineffective said power means.

8. In a drilling machine, a head; a spindle translatable mounted therein; power means for translating said spindle; means connected with the spindle to counterbalance the weight thereof; a bar slidably mounted in said head substantially parallel with the spindle and provided with a plurality of shoulders; a normally inoperative latch device carried by said spindle 115 and adapted, upon failure of said counterbalance, to engage one of the shoulders on said bar thereby to lock said bar to said spindle, said bar thereafter having a limited sliding movement with said spindle; a cam on said 120 bar; and means actuated by said cam during said limited sliding movement to render said power means ineffective.

9. A drilling machine combining a vertically translatable spindle; power means including a 130 clutch for translating said spindle; means operatively connected with said spindle normally tending to counterbalance the weight thereof; means operable immediately by the failure of said last mentioned means to stop the translation of said spindle and to lock same against further movement; and means to release said clutch simultaneously with the operation of the spindle stopping means.

10. A drilling machine combining a vertically translatable spindle; counterbalancing mechanism for said spindle including an operative connection with said spindle; power means including a clutch for translating said spindle; means operable immediately by failure of said connection to release said clutch thereby to suspend the action of said translating means and simultaneously to lock said spindle against further movement.

11. A machine tool combining a frame; a ver- 150

5 tically arranged translatable tool spindle supported thereby; selectively operable manual and power means for translating said spindle, said power means including a clutch; counterbalancing means for said spindle; means to release said clutch immediately by failure of said counterbalancing means; and means for automatically locking said spindle against further movement.

10 12. A machine tool combining a vertically arranged translatable spindle; power means in-

cluding a clutch for translating said spindle; means to counterbalance said spindle; and means rendered operable immediately upon breakage of said counterbalancing means to open said clutch thereby to stop the power translation of said spindle and to lock the spindle against further movement.
